UNITED STATES PATENT OFFICE.

HYMAN MAIMIN AND AUGUST FREDDY, OF NEW YORK, N. Y., ASSIGNEES TO H. MAIMIN CO., INC., A CORPORATION OF NEW YORK.

CLOTH-CUTTING MACHINE.

Application filed April 27, 1921. Serial No. 464,927.

To all whom it may concern:

Be it known that we, HYMAN MAIMIN and AUGUST FREDDY, citizens of the United States of America, residing at New York, 5 county of New York, and State of New York, and whose post-office address is 251 West 19th street, New York city, New York, have invented certain new and useful Improvements in Cloth-Cutting Machines; and we do hereby declare the following to be a full, clear, and exact description of the invention, such as will enable others skilled in the art to which it appertains to make and use the same.

15 This invention relates to cloth-cutting machines, and particularly to the knife guard and sharpening stones, and means for mounting them upon the machine.

It is necessary to provide power-driven 20 cloth-cutting machines with guards protecting the hands of the worker from the edges of the knife. In the case of rotary blades, the rear edge is permanently protected, but this is, in the nature of things, 25 impossible with the forward or cutting edge, the guard for which cannot extend below the upper surface of the cloth being cut, and which must be vertically adjustable for 30 lays of different thicknesses. At the same time the guard performs the secondary function of the pressure foot.

It is also necessary to provide such machines, particularly those of the rotary blade type, with grinding attachments, by means 35 of which the blade may be periodically sharpened without interference with the normal operation of the machine. The sharpening device commonly used consists of a pair of loosely mounted abrasive 40 wheels carried by a supporting yoke pivotally mounted on the frame of the machine, normally urged away from the blade by means of a spring, but readily movable into grinding contact with the knife edge when 45 the necessity arises.

As both knife guards and sharpening means are practical necessities, the problem has arisen of providing cloth-cutting machines with both in such a manner that 50 they shall not mutually interfere with each other. To do this it has been proposed to mount the grindstones wholly behind the guard so that they be swung downward into contact with the upper edge of the blade 55 without necessitating any movement of the

guard. This is satisfactory, but a different sharpening action is obtained by swinging the stones into contact with the lower part of the blade. To do this it is, of course, necessary that the guard be temporarily 60 moved aside during each grinding period, or positioned so far in advance of the cutting edge as to make it practically useless as a protection. Consequently mechanisms have been devised for moving the 65 grindstones into contact with the blade while simultaneously moving the guard to one side, and returning the latter to its original position as the grindstones are swung back. These movements have been 70 effected through trains of gears. Such gearing is objectionable in that it is unnecessarily complex; but more than that, the arrangement does not permit of a rigid locking of the guard in its operative position, 75 and this, of course, is essential if the guard is to be effective.

It is therefore an object of the present invention to mount a knife-guard and sharpening stones on a cloth-cutting machine so that as the stones are swung into grinding contact with the blade, the guard is moved directly aside without the intermediary of gearing or linkage, and so that when the guard is returned to its protecting 80 position it shall be rigidly locked in place. This object is attained by providing the yoke in which the grindstones are journaled with a cam surface which engages the guard in any position of vertical adjustment and 85 is provided at one side with a locking groove or channel in which the guard is rigidly seated and held when the stones are in inoperative position.

A further object of the invention is to 90 provide a simple and effective clamp for readily holding the guard in any position of vertical adjustment determined by the thickness of the cloth being cut.

The nature of the invention will be more 95 clearly understood after a study of the accompanying drawings which disclose certain preferred embodiments thereof, and in which Fig. 1 is a side view of a cloth-cutting machine equipped with the guard and 100 sharpening means mounted thereon in accordance with this invention; Fig. 2 is an end view of the same machine showing the guard in operative position; Fig. 3 is a side 105 view of the machine looking at it from the 110

reverse side from that shown in Fig. 1; Fig. 4 is an end view on an enlarged scale showing the grindstones in operative contact with the blade and the guard moved aside into inoperative position; and Fig. 5 is a horizontal section taken through the machine just below the motor casing and showing more clearly the means for locking the guard in its operative position.

10 The cloth-cutting machine shown in these drawings is of the rotary blade type and comprises a motor casing 1 mounted upon a standard 2 carried by a base plate 3. The machine is provided with the ordinary 15 rotary knife 4 driven by the motor in the usual way and the machine is moved over the cutting table and guided by means of the handle 5. The foregoing is a common construction and forms no part of the present invention.

10 The forward or cutting portion of the knife blade 4 is protected by means of a guard 6 supported in vertical adjustment by means of the pinch clamp 7 which is pivoted to the forward side of the motor casing. This clamp comprises two plates or wings 8 provided with holes 9 through which the guard 6 passes. When the wings 8 are parallel these holes 9 are in alignment and because of a relatively loose fit permit longitudinal movement of the guard. When, however, these wings are not parallel the holes 9 are not in perfect alignment and the guard is clamped by means of the binding action of the wings. In order that the guard shall normally be held in a fixed position the clamp is provided with a spring 11 normally forcing the wings outwardly. The longitudinal adjustment of the guard is effected by pinching the wings 8 together by means of the thumb and finger until they are parallel and then sliding the guard to the desired position. A pin 10 projecting inwardly from one of the wings limits their inward movement so that when this pin contacts with the other wing the two are parallel. The guard is held in its vertical and operative position by means of an expansion spring 12 seated upon a lug 13 projecting outwardly from the forward side of the motor casing, and bearing against an extension 14 of the lower plate or wing of the pinch clamp, this spring tending to swing the clamp about its pivot and bring the guard into vertical position.

15 The sharpening means comprises a pair of independent abrasive wheels 20 each designed to contact with one side of the cutting edge of the blade 4. These stones are 20 loosely mounted in a yoke 15 which is pivoted at 16 upon the frame of the machine below the motor casing and above the rotary blade. A spring 17 wound about the pivot pin tends to lift the stones upward and out of contact with the blade. The stones are

25 swung into contact with the blade by means of a series of links 18 operatively connected with the yoke 15 and extending rearwardly beneath the motor casing and terminating in a trigger 19 adjacent the handle 5.

30 During the cutting operation the guard 6 is in its vertical position as shown in all of the figures except Fig. 4 and the grindstones are elevated. When in this position the guard 6 is rigidly held by means of a locking channel or groove 21 on the rear surface of the yoke 15, as clearly shown in Fig. 5. When the guard is held within this groove it is practically impossible to move it laterally in any direction. When the 35 blade has become dulled through cutting and it becomes necessary to sharpen it, the operator, without taking his hand from the handle 5, pulls upon the trigger 19. This causes the yoke 15 to swing downwardly and assume the dotted line position shown in Fig. 1, and at the same time causes the guard 6 to ride outwardly over a cam surface 22 on the rear surface of the yoke. This position is shown most clearly in Fig. 4. 40 This cam surface 22, as shown most clearly in Figs. 4 and 5, is contiguous to the groove 21 and is so designed that downward movement of the yoke unlocks the guard and moves it laterally of the blade. This swings the guard and the pinch clamp 7 about the pivot of the latter and compresses spring 12 against the lug 13. As soon, therefore, as the grinding operation is complete and the operator releases the pressure of his finger 45 upon trigger 19, spring 17 throws the grindstones upwardly and spring 12 swings the guard back into its vertical position. As a result of these two movements the guard is snapped into the locking groove 21 and 50 held again rigidly in its operative position.

55 Although the invention has been shown and described in connection with a cutter of the rotary blade type, and in this connection will undoubtedly find its greatest usefulness, it is clear that the principle involved is applicable to blades of the reciprocating type. Furthermore the forms shown are to be considered as illustrative only and modifications in the mechanism may be 60 readily effected without departing from the true spirit of the invention.

65 We claim:

1. In a cloth-cutting machine the combination of a cutting blade, a guard therefor, a grindstone for sharpening the blade, a yoke supporting the grindstone and pivotally mounted on the frame of the machine, a cam surface on the yoke designed to contact with the guard, and means for swinging the grindstone into contact with the blade and simultaneously moving the guard outwardly on the cam surface.

2. In a cloth-cutting machine the combination of a cutting blade, a guard therefor,

a grindstone for sharpening the blade, a yoke supporting the grindstone and pivotally mounted on the frame of the machine, a locking groove in the yoke in which the 5 guard is normally held in operative position, a cam surface on the yoke contiguous to the locking groove, and means for swinging the grindstone into contact with the blade and simultaneously moving the guard 10 out of the locking groove and outwardly on the cam surface.

3. In a cloth-cutting machine the combination of a cutting blade, a guard therefor, a grindstone for sharpening the blade, a 15 yoke supporting the grindstone and pivotally mounted on the frame of the machine, a locking groove in the yoke in which the guard is normally held in operative position, a cam surface on the yoke contiguous 20 to the locking groove, means for swinging the grindstone into contact with the blade and simultaneously moving the guard out of the locking groove and outwardly on the cam surface, and means for returning the 25 guard to the locking groove when the grindstone is swung into inoperative position.

4. In a cloth-cutting machine the combination of a cutting blade, a guard therefor

pivotsally mounted on the frame of the machine, a grindstone, a yoke supporting the 30 grindstone pivotally mounted on the frame of the machine, and a cam surface on the yoke designed to contact with the guard, the arrangement of the parts being such that as the grindstone is swung into grinding contact with the blade the guard rides upon the cam surface and is swung out of 35 operative position.

5. In a cloth-cutting machine the combination of a cutting blade, a guard therefor, 40 a clamp pivotally mounted on the frame of the machine holding the guard in adjustment, a grindstone, a yoke supporting the grindstone and pivotally mounted on the frame of the machine, a cam surface on the yoke designed to contact with the guard in any position of adjustment of the latter, and means for swinging the grindstone into 45 grinding contact with the blade, thereby causing the guard to ride upon the cam surface and swing out of operative position. 50

In testimony whereof we affix our signatures.

HYMAN MAIMIN.
AUGUST FREDDY.
